KNITTING MACHINE

William A. Zieve, Brooklyn, N. Y.

Application May 13, 1936, Serial No. 79,444

8 Claims. (Cl. 66—25)

This invention relates to knitting machines in general, and is herein illustrated as especially designed for use in association with a circular knitting machine of the type in which the needle cylinder and needle dial remain stationary and reciprocatory movement is imparted to the needles through the instrumentality of appropriate needle-actuating cams.

An important object of the invention is to provide a generally improved and simplified knitting machine, which is characterized by the fact that it is so constructed as to make possible the use of a relatively large number of feeds and by the fact that various adjustments, changes and alterations, such as are required, for example, when changing the machine set-up according to the design or type of fabric to be knitted, may be easily and expeditiously accomplished without necessitating the exercising of so much as ordinary skill on the part of the operator.

Other objects and advantages of the invention will become apparent from the following description, when taken in connection with the accompanying drawings in which—

Fig. 1 is a fragmental view in plan of a knitting machine constructed in accordance with the present invention, Fig. 2 is a vertical sectional view taken on line 2—2 of Fig. 1, Fig. 3 is a view in elevation of so much of the machine as is shown in Fig. 1, Fig. 4 is a view showing in front elevation one of the pattern wheel units appearing in Figs. 1 and 3, and Fig. 5 is a sectional view taken on line 5—5 of Fig. 4.

Referring to Fig. 2, it will be noted that the horizontal needles 10 and the vertical needles 11 are carried, respectively, on a stationary needle plate 12 and a stationary needle cylinder 13, with the former of which there is associated the usual dial cam plate 14 and with the latter of which there is associated the usual cam ring 15.

Mounted on the dial cam plate 14, are a plurality of feed units 16, each of which includes a radially disposed bar or block 17, provided at one end with a slot 18, and formed intermediate its ends with a notch 20 and at its outer end with a notch 21. The slot 18 is adapted for the reception of a retaining pin 22, which is secured to the dial cam plate 14 and to the upper end of which is pivotally connected a latch bolt 24, the screw threaded or nut-carrying end of which is adapted to assume a position within the upwardly extended slotted arm 25 of an angle bracket 26 secured to the bar 17. The notch 20 is adapted to accommodate a retaining pin 27, which is carried by the dial cam plate 14. It will be observed that the notch 20 is relatively large with respect to the pin 27 so as to permit various lateral adjustments of the bar 17 to be made. In order that the bar may be held in intimate face-to-face engagement with the dial

cam plate 14, the upper or screw threaded end of the pin 27 is provided with a wing nut 28, the base 30 of which is sufficiently large to completely overlie the notch 20 regardless of any position of adjustment that the bar 17 may assume. Secured to and depending from the outer end of the bar 17, is a cam-carrying lug 31 to which is connected a horizontally disposed centripetal cam 32 which may be regarded as a low-

5

10

Each of the feed units 16 further includes a horizontally disposed centrifugal cam 34, (which may be regarded as a lifting cam) connected to a cam-carrying lug 35, secured to and depending from a block 36, which corresponds in certain respects to the bar 17 hereinbefore described. The block 36 when placed in position on the dial cam plate 14 assumes a fixed relation to that plate inasmuch as it is provided with a pair of pins 37, which are adapted to be received by and to snugly fit within a pair of pocket-like openings 38, with which the dial cam plate is provided. The inner end of the block 36 is provided with a notch 40, adapted to receive a retaining pin 41, which is secured to the dial cam plate 14 and the upper or screw threaded end of which is provided with a wing nut 42, by which the bar may be held in intimate face-to-face engagement with the dial cam plate. Secured to the block 36 is an angle bracket 44, the upwardly extended slotted arm 45 of which is adapted to receive the screw threaded or nut-carrying end of a latch bolt 46, which is pivotally connected to a pin 47, carried by the bar 17 which is next adjacent the block 36 at the left 20

35

thereof, as viewed in Fig. 1. From the foregoing, reference being had particularly to the latch bolts 24 and 46, it will be appreciated that the former bolts serve to anchor the bars 17 against a normal tendency to move radially outwardly incident to the drag of the cams 32 over the horizontal needles as the dial cam plate 14 is rotated in the direction of the arrow A appearing in Fig. 1 and that the latter of these bolts serve to anchor the bars against a normal tendency to creep or pivot about the pins 22 in a clockwise direction as viewed in Fig. 1 incident to travel of the cams 32 over the horizontal needles. Aside from the fact that the latch bolts 24 and 46 serve to insure against undue displacement of the bars 17 in the manner just described, they may be utilized, upon backing off the wing nuts 28, to facilitate micrometric radial adjustment of the bars 17 as well as pivotal adjustments thereof about the pins 22, as when such adjustments are desired to effect proper positioning of the cams 32 in setting up or otherwise conditioning the machine for use.

With the block 36 there is associated a dial pattern wheel 48, which is provided with the 60

usual spirally cut peripheral teeth 50, between certain of which, according to the design of the pattern to be produced in the knitting operation, are carried the usual form of jacks 51. The pattern wheel 48 is adapted to cooperate with certain of the horizontal needles 10, depending upon the arrangement of the jacks 51, to move such needles outwardly pursuant to their being acted on by the preceding centrifugal cam 34, as is well known in the art. As shown most clearly in Fig. 5, the pattern wheel 48 is carried by a sleeve bearing 52, on which is also carried a jack-retaining plate 54, which is held in position by a nut 55, carried on the screw threaded portion of the bearing sleeve. In order that the nut 55 may be locked in a definite position on the bearing sleeve 52 it is provided with a yoke-like spring 56, the inturned ends of which are pivotally supported in the wall of the nut at diametrically opposite points thereon. The nut 55 is provided, as at 57, with a notch into and out of which the yoke portion of the spring 56 may be sprung, the function of the notch being to retain the spring normally in its position shown most clearly in Figs. 1 and 4. Referring to Fig. 5, it will be noted that one of the inturned ends 58 of the spring 56 is of a length substantially greater than the thickness of the wall of the nut 55 so as to enable it to enter an opening 60 formed in the wall of the bearing sleeve 52, the opening 60 being so located that the end 58 of the spring will enter the same as the nut 55 is run down on the bearing sleeve 52 and at such time as the nut exerts through the jack-retaining plate 54 a proper clamping action on the jacks 51.

The pattern wheel unit U thus far described as comprising the wheel 48, jacks 51, jack-retaining plate 54, nut 55 and spring 56, is adapted to be readily assembled in the machine or removed therefrom as will be readily understood when it is taken into account that the unit is rotatably supported on a readily detachable bearing pin or shaft 61. The bearing pin or shaft 61 is formed at one end with a head 62, and for the purpose of insuring proper lubrication it is provided with a central oil passage 64, which communicates with an oil duct 65, leading outwardly to the bearing surface and there communicating with a spiral groove 66, into which oil is delivered from the passage 64 and duct 65. The pin 61 is formed with a shank 67, which is adapted to snugly fit within an opening 68, formed in a bearing support 70, which is vertically adjustable in the block 36 and is adapted to be held in various positions of adjustment by a cooperating set screw 69. Because of the nicety of fit of the shank 67 with respect to the opening 68, the wheel unit is, of course, held on a definite axis at all times. In order that the shank 67 may be held against longitudinal movement, there is provided a retaining pin 71, which is slidably carried within the bearing support 70 and is adapted to register with a circumferential notch 72 formed on the shank 67, the pin 71 being normally retained in locked position by a tension spring 74 one end of which is connected to the upper end of the pin and the other end of which is suitably anchored to the upper end of the bearing support 70. The end of the shank 67 is rounded, as shown in Fig. 5, and will cam the retaining pin 71 upwardly against the action of the spring 74 as the shank is inserted in the opening 68 and the bearing pin 61 is moved to its position shown in Fig. 5, following which it becomes necessary to manually lift the retaining

pin from the circumferential notch 72 in order to permit the bearing pin to be removed.

With the cam ring 15 there are associated a plurality of feed units 75, which correspond in number to the feed units 16 hereinbefore described and each of which includes a radially disposed block 76, carrying a pair of locating pins 77 which are accommodated within suitable openings formed in the cam ring 15. The block 76 is secured in a fixed position on the cam ring 15 by a wing nut 78, carried at the upper end of a screw threaded stud 80, projecting upwardly from the cam ring and extending through the outer end of the block. Carried at the inner end of the block 76, are a pair of guide pins 81 and 82, accommodated within openings 84 and 85, formed in a vertically adjustable cam block 86, to which is suitably connected a needle lowering cam 87 which is adapted to cooperate with the vertical needles 11 to move them downwardly and with respect to which the cam 32 is both circumferentially and radially adjustable. The cam 87 presents a curved inner surface, conforming generally to the contour of the needle cylinder 13 and is provided at its left margin, reference being had to Fig. 3, with a vertically adjustable stop finger 88, adapted to prevent overthrow of the needle under the action of the respective needle lifting cams hereinafter more particularly described. In order that the cam block 86 together with its associated cam 87 may be vertically adjusted with relation to the corresponding needle elevating cam just mentioned, the guide pin 82 is provided with an encircling compression spring 90, opposite ends of which are accommodated within sockets 91 and 92 formed respectively in the blocks 76 and 86, and is further provided at its upper or screw threaded end with a nut 93, between which and the spring 90 the block 86 is held in various positions of adjustment as determined by the position of the nut 93 on the screw threaded guide pin 82. In order to insure the nut 93 against undue displacement, once a proper adjustment of it has been effected, there is provided a retaining spring 94, one end of which is anchored to the block 86 and the other end of which is adapted to bear firmly on one or another of the faces of the nut.

Each of the feed units 75 further includes substantially a radially disposed block 95, which is secured to the cam ring 15 similarly to the block 76 hereinbefore described and to which is secured a cam block 96, provided at its inner end with a needle lifting cam 97, the inner face of which conforms generally to the contour of the needle cylinder 13. On the cam block 96, is carried a pattern wheel unit U', which is structurally identical to the pattern wheel unit U hereinbefore described and which is adapted to be quickly attached to and removed from its operating position on the cam block in the manner already described in connection with the wheel unit U.

In view of the nature of the machine with which the present invention is illustrated, it is believed that no detailed description of the operation of the machine proper is here necessary, but it is deemed advisable to point out the fact that the feed units 16 and 75 embodying the present invention are such as to make possible the use of a substantially greater number of feeds in a given size machine than has been permitted heretofore. In this connection it is to be observed that the arrangement of the essential elements 75

entering into the structure embodying the invention are such as to account for a very substantial saving of space and that such conservation of space makes possible the placing of the feeds closer together throughout the general perimeter of the machine. Aside from the fact that the structure enables a greater number of feeds to be employed in connection with a given size machine, it will be especially observed that the various parts, such as the several cams and other elements about which the invention centers, are readily accessible, may be easily removed, may be readily adjusted, changed or altered as conditions may demand as, for example, when it becomes necessary to effect relative adjustment between the several needle actuating cams, change pattern wheel units, or alter the pattern wheel units by changing the arrangement of jacks therein.

Although only one form of the invention is herein shown and described, it will be understood that various modifications may be resorted to without departing from the spirit of the invention or the scope of the following claims:

What is claimed is:

1. In a knitting machine, a feed including a pair of feed units, each comprising a pair of blocks disposed in a contiguous relation, needle actuating cams individual to and carried by said blocks, and means for supporting one block of one of said units for adjustment lengthwise of itself and for pivotal adjustment about a given axis whereby an adjustment corresponding to the resultant adjustment of that block may be effected between its associated cam and the cam associated with the corresponding block of the other unit.

2. In a knitting machine, a feed including a pair of feed units, each comprising a pair of blocks disposed in a contiguous relation, needle actuating cams individual to and carried by said blocks, means for supporting one block of one of said units for adjustment lengthwise of itself and for pivotal adjustment about a given axis whereby an adjustment corresponding to the resultant adjustment of that block may be effected between its associated cam and the cam associated with the corresponding block of the other unit and means for effecting micrometric adjustment of said one block lengthwise of itself and for effecting micrometric pivotal adjustment thereof about said given axis.

3. In a knitting machine, a feed including a pair of feed units, each comprising a pair of blocks disposed in a contiguous relation, needle actuating cams individual to and carried by said blocks, means for supporting one block of one of said units for adjustment lengthwise of itself and for pivotal adjustment about a given axis whereby an adjustment corresponding to the resultant adjustment of that block may be effected between its associated cam and the cam associated with the corresponding block of the other unit and means for effecting micrometric adjustment of said one block lengthwise of itself and for effecting micrometric pivotal adjustment thereof about said given axis and for anchoring said one block against a normal tendency to move lengthwise of itself and about said given axis under the action of its associated cam against the needles with which that cam is adapted to cooperate.

4. In a knitting machine, a feed unit comprising a pair of blocks disposed in a contiguous relation, a needle actuating cam individual to and

carried by each of said blocks, the cam of one block being adapted to exert a needle thrust in one direction and the cam of the other block being adapted to exert a needle thrust in an opposite direction, and means for supporting said blocks together with their associated cams in operative positions and in positions to be removed independently of each other.

5. In a knitting machine, a feed including a pair of feed units, each comprising a pair of blocks disposed in a contiguous relation, needle actuating cams individual to and carried by said blocks, means for supporting one block of one of said units for adjustment with respect to the corresponding block of the other of said units whereby a relative adjustment may be effected between the cams carried by said corresponding blocks, and means for effecting micrometric adjustment of said one block with respect to the corresponding block of the other of said units and for anchoring said one block against a normal tendency to move under the action of its associated cam against the needles with which that cam is adapted to cooperate, the latter means comprising a latch bolt pivotally supported at one end and provided at its other end with a nut adapted when moved in one direction to effect a corresponding movement of said one block.

6. In a knitting machine, a feed including a pair of feed units, each comprising a pair of blocks disposed in a contiguous relation, needle actuating cams individual to and carried by said blocks, means for supporting one block of one of said units for adjustment lengthwise of itself and for pivotal adjustment about a given axis whereby an adjustment corresponding to the resultant adjustment of that block may be effected between its associated cam and the cam associated with the corresponding block of the other unit and means for effecting micrometric adjustment of said one block lengthwise of itself and for effecting micrometric pivotal adjustment thereof about said given axis, the latter means comprising a pair of latch bolts, each of which is pivotally supported at one end and provided at its other end with a nut adapted when moved in one direction to effect a corresponding movement of said one block.

7. In a knitting machine, a feed including a pair of feed units, each comprising a pair of blocks disposed in a contiguous relation, needle actuating cams individual to and carried by said blocks, means for supporting one block of one of said units for adjustment with respect to the corresponding block of the other of said units whereby a relative adjustment may be effected between the cams carried by said corresponding blocks and a pattern wheel unit carried by one block of each of said units.

8. In a knitting machine, a feed unit comprising a pair of blocks disposed in a contiguous relation, needle actuating cams individual to and carried by said blocks, the cam of one block being a lifting cam adapted to exert a needle thrust in one direction and the cam of the other block being a lowering cam adapted to exert a needle thrust in an opposite direction, means for supporting said blocks together with their associated cams in operative positions and in positions to be removed independently of each other and a pattern wheel unit carried by that block on which said lifting cam is carried.

WILLIAM A. ZIEVE.
